UNITED STATES PATENT OFFICE

2,249,083

PROCESS FOR STAPLING CONTINUOUS ARTIFICIAL FIBER

Rudolf Kern, Gladbach-Rheydt, Germany

Application June 28, 1939, Serial No. 281,709
In Germany December 30, 1937

2 Claims. (Cl. 19—1)

In the manufacture of cellulose wool, continuous artificial fiber bands having the individual fibers thereof running parallel to each other are normally cut into staples and then forwarded to the mechanical spinners in a mixed condition as raw material, that is, cellulose wool. The mechanical dressing and preparation, for instance, in the drawing apparatus and combing by the cotton spinners, required for forming a capable spinning band with more or less parallel fiber layers, not only represents a lengthy and expensive procedure, which for many purposes could be entirely dispensed with, but also considerably spoils the uniformity of length, stretching capacity and original breaking power of the fibers.

Various methods and devices have heretofore been developed for the direct stapling and immediate continuation of spinning of continuous artificial fiber bands, by which, for instance, the fiber cable, which has gradually been torn through exceptional pressure between the pairs of drawing cylinders and the fiber pieces, are thereby gathered for further spinning. But, this manner of work improperly forms the length of the fiber staples obtained within the distances between the pressure points of two pairs of drawing cylinders, as a result of which the staples immediately fall from their bands, whereupon, the spinning material thus obtained only partially fulfills the purposes of the cellulose wool spinning mill, and does not at all meet the demands of the cotton drawing frame spinning mill.

According to another process, artificial fiber bands with periodically deviating transfer sections of the individual fibers are produced, so that these, in the following step in the drawing frame, tear at weakened points. In the cases mentioned, the fibers are pulled and loaded far beyond their elastic stretching limit, whereby they lose a considerable portion of their tearing power and other properties important to the bearing of the textures.

Trials have been made cutting endless fiber bands in staples of desired length by means of short knives arranged on rollers and then drawing out immediately thereafter these shaving-like joined band or ribbon cuttings. As a result thereof, the fibers which have been passed out sideways by the prearranged small knives can be present in the fiber band either unstapled or stapled in an indefinite length, whereby their draft is influenced especially in the cotton drawing frame spinning mill, which is entirely dependent on the fiber length.

The process of the present application eliminates fiber-spoiling mechanical preparation proceedings. Thus, for instance, every carding, combing and unnecessary drawing of the bands or ribbons is excluded. It therefore does away with every superfluous demand on the fibers and every shortening and weakening thereof. It avoids, furthermore, a sideward expanding of the slubbing when stapling and by that, prevents the passing through the machine of unstapled fiber masses. The fiber masses themselves in their union, for instance, the slubbing band, have the fibers hung together almost in their entire length and they lie with their fiber points inside the slubbing and their ends are directed towards the bulk.

The principal object of the present invention is to provide a process and apparatus therefor which will permit the stapling of artificial fibers without the loss of fibers or injury to the natural characteristics thereof and to collect said staple fibers in such a manner that the same, with very slight deviations at their end, will be held together for nearly their entire length.

Further objects of the invention will be in part obvious and in part pointed out in the following description of the accompanying drawings.

In the drawings:

Fig. 1 is a schematic view of one manner of cutting a fiber band.

Fig. 2 is a schematic view of a modified form of cut for fiber bands.

Fig. 3 is a schematic view of a second modification of a cutting of fiber bands.

Fig. 4 is a detail side view of a continuous cutting device.

Fig. 5 is a front view of Fig. 4.

Fig. 6 is a front view of a modified form of cutting device.

Fig. 7 is a side plan view of a device for stapling and collecting fibers, and

Fig. 8 is a side view of a machine for stapling and collecting artificial fibers.

Referring now more particularly to the accompanying drawings wherein like and corresponding parts are designated by similar reference characters, *a* designates a band or ribbon (Fig. 1), which consists of single fibers arranged parallel to each other, continuously cut through relative to its running direction at a sharp angle so that the section *b* (Figs. 1 and 2) forms a ribbon of adhering fibers which are relatively long and are thereby simultaneously caught, i. e., held together by several successive drawing cylinders

I, II and III (Figs. 1 and 2) of the pressure lines *k*. As these part sections in strips, sections *b*, in rows and side by side follow one after the other, however, the single cuts do not, as is the case with the ordinary cutting perpendicular to the length of the band, fall apart but remains intact after the cutting. This is favored by the fact that the fibers, as a result of their ends being only slightly pushed against each other, stick together nearly throughout their entire length and, therefore, retain the largest possible mutual friction.

The invention is more closely described here-with on the strength of a schematic example of its execution.

Upon rolling a sharp edged worm, such as a spiral knife or the like *s* under pressure on a sub-cylinder *u* (Figs. 4-6) and inserting a ribbon of continuous artificial fiber, which eventually expands between this pair of cylinders, the moving worm or spiral knife points slowly cut the fiber band at the given pressure points, thus at an angle. The number and pitch of the threads of the spiral knife or the like determines the staple length which can be obtained, as the following threads can separate one and the same fiber at previously fixed intervals a second time, a third time, etc. The progress of the cut of the total width is shown schematically in Figs. 1 and 2.

For instance, an applied three course spiral knife *s* of 48 mm. diameter and 18 mm. thread rolling on sub-cylinder *u* would yield an approximate staple length of 15 mm., while a 36 mm. wide fiber band would, with every knife point, cut through all together, about 300 mm. consecutive lengths of fiber, according to Fig. 1. It appears especially favorable to insert a fiber band, according to the example shown in Fig. 6, with the halves thereof each under a right and left coursed cutting spindle, whereby not only eventual side pressures of the cutting spindle against the fiber band is done away with, but also, according to Fig. 3, all of the entering points *c* of the individual sections are arranged inside the ribbon breath, while in each case the points *d* (Fig. 3) subjected to the draft, lie at the outer edges of the ribbon. To avoid band breakages in the drawing frame, respectively between each two pairs of drawing cylinders, this arrangement appears especially suitable.

The gripping of the fiber by the latter arrangement is shown in Fig. 3 and discloses the especially favorable drafting condition thereof.

According to this process, but before inserting the draft, the fibers which are still held fast by the drawing cylinder pairs after stapling, form flat rhombs which are slipped one into the other like fingers and on the points of which the draft sets in in echelons in every uniform rotation. This unusual symmetrical arrange-

ment appears especially adapted for the production of even and smooth yarns.

In Fig. 7 is schematically shown an example according to the present process for an unwinding, stapling and drawing arrangement. From coil 2 carrying the continuous artificial fiber band *a*, the band goes over a delivery and spanning device 4-6 into the staple arrangement 8, 8 and after that into the drawing frame 13, 13', 14, 14', 15, 15', after which it is further spun in the known manner. This arrangement may be changed as desired and the staple arrangement can be operated as an independent aggregate under separation of the following drawing frame.

The device can also be arranged directly on the drawing arrangements of flyers. It can also be put or worked in conjunction with them as a separate independent aggregate in front of such machines. Such an arrangement is shown in Fig. 8. In the creel 1 are inserted those bobbins which contain the continuous artificial fiber ribbon. The cables 3 run from here into the pair of feed rollers 4 and from there over table 5 which is shaped tray-like at its front end 6 towards the cutting roller pair. The tray 6 works together with an upper roller 7, which can be suitably loaded. From the pressure between tray 6 and upper roller 7, the fiber material can be drawn over cutting cylinder 8 on which the cutting or knife roller 9 rests. The cutting or knife roller 9 is adjustable elastically by spring 10 and hand wheel 11. The fiber material which is passed through these pairs of rollers 8, 9 is cut diagonally, according to Figs. 1-3. It goes to the drawing frame either directly or, in this case, over a table 12 which consists of roller pairs 13, 14, 15. On leaving the pairs of rollers, the distorted parallel fiber bundles 16 are twisted by spindles 17.

Manifestly, the construction herein shown is capable of considerable modification and such modifications as come within the scope of my claims, I consider within the spirit of my invention.

I claim:

1. Process for the stapling and drafting of continuous artificial fiber-bands consisting in cutting said bands in a continuous manner into ribbons which latter extend diagonally from the outer edge of the band and meet in the medial portion of the band considerably rearward of the edge cut and pressing the fiber ends towards one another.

2. Process for the stapling and drafting of continuous artificial fiber-bands consisting in cutting said bands in ribbons which latter extend diagonally from the edges of the band towards the middle thereof and pressing the fibers towards one another.

RUDOLF KERN.
